[57] **ABSTRACT**

Method and apparatus for treating discontinuous sheets such as animal hides. The hide is placed on a moving conveyor. At least one pair of elements are arranged to rotate above the conveyor and in a horizontal plane with respect to it. The elements are arranged on axes which are in tandem along the edge of the conveyor and the elements are moved to engage the hide in a sector of a circle the beginning of which lies along a line normal to the direction of movement of the conveyor and has a path extending arcuately to the peripheral edge of the conveyor. The elements at the front of the conveyor rotating in the direction of movement of the conveyor while that in the rear in the opposite direction.

METHOD OF SURFACE TREATING DISCONTINUOUS SHEET MATERIALS

BACKGROUND OF INVENTION

The present invention relates to a method of surface treatment of discontinuous or defined pieces of sheet material, and in particular to a method and apparatus for working leather hides and the like.

Apparatus for the surface treatment of leathers, particularly in hide form, employ machines with wide tools which are caused to engage the surface of the hide from side to side. Such tools as drum knives, dull scraper bars, or polishing rollers, are generally arranged to extend across the width of the material in an attempt to treat the entire surface of the material in one sweep of the tool. Because the thickness of the leather hide is non-uniform, particularly having a thick back portion extending centrally from the head to the hind ends, wide working tools do not function as efficiently as would be desirable. The hide must generally be subjected to after treatments such as for instance setting out, stretching, and pressing the hide in order to obtain the desired uniformity of thickness in the finished leather piece. Such after treatment adds to the cost and complexity of the treatment process and is both laborious and cumbersome requiring considerable effort. Often manual manipulation of portions of the leather is required adding a dangerous aspect to the process.

The manual spreading of hides has been replaced by the so-called automatic through-put spreading. This new technique has raised the productivity in the treatment of sheet materials. In treating sheet materials of a continuous form, spreading brushes may be used having a rectilinear or even a rotational movement. When applied to the treatment of leathers having very irregular shape, numerous problems may result. For example, not only are the edges of the leather material subject to folding but the very irregular peripheral parts of the hide may be torn or ripped from the main body of the hide. This is particularly true with the rather long leg portions of the hide. Even under the most favorable conditions for this continuous process the coat surface of the peripheral portions of the hide remain improperly spread during treatment.

It is the object of the present invention to provide a method and an apparatus for the surface treatment of discontinuous sheet materials, in particular leather hides, which overcome the disadvantages of the prior devices.

It is the object of the present invention to provide apparatus and method by which the surfact treatment of leather hides can be made so that a more uniform treatment occurs, and wherein the non-uniform thickened portions of the hide may be treated to provide for a more uniform thickness of the finished product.

It is a further object of the present invention to provide a method and apparatus wherein the surface treatment of leather hides may be simplified and speeded up so that increased productivity may be obtained while simultaneously reducing the laborious and cumbersome manual handling of the leather hide.

The foregoing objects, others, as well as numerous advantages of the present invention will be seen from the following disclosure of the preferred embodiment.

SUMMARY OF INVENTION

According to the present invention a method and apparatus is provided for the work of discontinuous sheet material such as animal hides wherein the animal hide is placed on a linearly moving conveyer and is contacted by working elements tandemly arranged along the side of the conveyer which rotate in opposite direction about individual axes of rotation perpendicularly disposed with the surface of the conveyer. The working elements are caused to move in an operating path wherein they engage the surface of the hide in an area defined by a sector of a circle, the beginning of which is located along a line normal to the direction of movement of the conveyer and in a path which extends arcuately toward the peripheral edge of the conveyer. The forward element of the tandem pair rotates in a direction corresponding to the movement of the conveyer while the rear element of the tandem pair rotates oppositely thereto.

Preferably two pair of tandemly arranged working elements are provided, a pair being disposed along each of the sides of the conveyor. The forward elements of each of the tandem pair as well as the rear elements are aligned with respect to each other along a line which is normal to (or perpendicular to) the direction of movement of the conveyer. The respective elements in each of the tandem pairs is rotated in directions contrary to those of the corresponding elements in the opposed tandem pair. Consequently, each of the elements engages the surface of the hide in a circular sector beginning from within the major portion of the hide directed either forwardly or rearwardly to the peripheral portions thereof.

Furthermore, the working elements are of such a length, and their axes of rotation are arranged at selected positions so that their sweep extends in overlapping areas, along the axial center of the conveyer as well as in a transverse area between the forward and rear elements, so that the more thickened portion of the hide will be worked by overlapping working elements. Full details of the present invention are set forth in the following description and are shown in the accompanying drawings.

BRIEF DESCRIPTION OF THE DRAWINGS

In the drawings FIG. 1 is a plan view of the present device in schematic form showing the conveyer and the rotating working elements and their relationship to the material being worked on.

FIG. 2 is a showing of the material worked showing diagrammatically the paths and working directions taken by the working elements.

FIG. 3 is a side view, partially in section, of the apparatus for carrying out the invention.

DESCRIPTION OF THE INVENTION

The methods for working the sheet material according to the present invention will be described initially with reference only to some of the means necessary for carrying it out.

Turning now to FIG. 1 a discontinuous sheet such as an animal hide 1 which is to be converted to leather, is placed on the surface of an endless belt conveyor 2. The conveyor is mounted in conventional manner to advance continuously in the forward direction shown by the arrow A. Suitable devices such as drive rollers,

idler rollers, tracking means, as well as motor drives are provided to effect construction and movement of the conveyor. Arranged above the conveyor are a plurality of surface treatment devices generally bearing the numerals 3, 4, 5 and 6. The devices comprise hubs 31, 41, 51 and 61 from which radially extend horizontal spoke-like surface treating elements, 32, 42, 52 and 62, respectively. The hubs 31, 41, 51, and 61 are mounted at their inner ends to shafts (not seen) which are journaled to extend perpendicularly to the conveyor along the respective edges of the conveyor. The treating devices are arranged in two tandem pairs 3, 5 and 4, 6 respectively. The forward and rear devices of each of the tandem pairs are aligned along the corresponding edge of the conveyor while the corresponding individual forward and rear members of each tandem pair are aligned transversely to the direction of the conveyor along lines 10 and 12.

Each device contains four surface treating elements 32, 42, 52 and 62 which are mounted on holders above the surface of the conveyor and are reciprocably movable toward and away from the conveyor so that they may swing about the shaft 4 in contact with a hide on conveyor. The shafts on which each of the devices are mounted are connected by suitable linkages, gears, or other transmission means to individual or common drives such as a motor, etc., so that they may be rotated in the directions indicated by the arrows R3, R4, R5 and R6 respectively. The devices rotate in opposite directions to each other, for example devices 3 and 6 rotate clockwise while devices 4 and 5 rotate counter-clockwise. Thus the forward devices 3 and 4 sweep counter to each other forwardly with respect to the movement of the conveyor in a path outwardly to the right and left edges of the conveyor respectively. The rear elements 5 and 6 sweep counter to each other rearwardly with respect to the direction of movement of the conveyor and outwardly to the right and left edges of the conveyor respectively. The direction of movement of the respective working elements are shown by the arrows 33, 43, 53 and 63, respectively.

The length of each of the spoke-like elements 32, 42, 52, and 62 are chosen so that each is greater than half the width of the conveyor. Consequently opposed elements 32, 42, 52 and 62 overlap the central portion of the conveyor by an amount indicated by the arrows B-B. Simultaneously the distances between the forward and the rear shafts of each pair of the devices 3, 5 and 4, 6 respectively are set so that the spokes overlap along the axial direction of the conveyor as indicated by the arrows C-C. The distance between the respective shafts on which the devices 3, 5 and 4, 6 are mounted may be adjusted so that this overlap C-C can be varied. Further, to avoid interference of the respective working elements of each of the devices, the elements are relatively offset so that as they rotate they mesh with each other in gear like fashion also as seen in FIG. 1.

The distance, i.e., the height of each of the elements above the conveyor may be adjusted by providing its supporting shaft with an axially moveable journal, or a telescoping extension or other similar conventional means. Preferably, however, the distance above the conveyor is selected to provide for a predefined thickness in the finished sheet or hide.

The spoke-like treatment elements are provided with means so that they may be lowered and raised during

each period of rotation. The elements are moved downwardly toward the conveyor and into engagement with the hide 1 when they each individually become located along the connecting transverse line 10 or 12 respectively and move in this operative position in a horizontal plane, parallel to the conveyor and an engagement with the surface of the hide in an arcuate path 33, 43, 53 and 63, respectively. Thus each of the elements is made to have an operative movement in which the element engages the works the surface of the hide defined by the sector of a circle substantially equal to one-fourth of each rotation. As soon as the element completes sweeping of its operating sector, the element is caused to be raised to insure its separation from the hide and/or the conveyor and in this raised position is caused to complete the remaining three quarters of the rotation. To accomplish this lowering and raising of the elements 32, 42, 52 and 62, the elements may be operated by a circular cam as they are caused to rotate by their mounting shafts.

In operation the hide is placed on the conveyor with the surface to be treated facing upwardly and the forward quarter of the hide place first in the direction of movement of the conveyor with the hind quarter facing upstream. In general the hide is arranged so that the central back portion lies along the center of the conveyor or beneath the overlapping section B-B. The hide may be positioned manually or by automatic means such as an infeed conveyor, drop feed or the like. The conveyor itself may be flat or may be provided with ridges, indents or other frictional holding means by which the hide may be securely held during the working operation. The conveyor and the spoke-like elements are continuously driven and rotated in a predefined relationship so that the working elements 32, 42, 52 and 62 may sweep over the hide in a predetermined and selected pattern while the hide is carried along by the conveyor so that the surface of the hide may be worked over its entire area.

The pattern of working of the hide is seen in FIG. 2. The elements 32 and 42 work the hide in a forward and outward arcuate pattern indicated by the arrows 33 and 43 while the elements 51 and 61 work the hide in a arcuate pattern rearwardly and outwardly as seen by the arrows 53 and 63. The respective patterns overlap and work the back of the hide along the section B-B and the overlapping axial portions C-C. In employing the apparatus, the method therefore provides that the constantly moving hide is worked by an array of elements which engage the surface of the hide initially in a position normal to the direction of movement and either move with the direction of movement or contrary to the direction of movement from within the thickened hide portion to its outward peripheral edges. The paths of movement are in all cases portions of a circle and at most one-quarter sectors thereof. The working elements always go from the thickened portion of the hide wherein the hide is more cohesive and strong to the outer peripheral edges conforming to the forward head and leg as well as the hind leg portions. As a consequence, the small extending portions of the hide are worked in the most proper and efficient manner so that they cannot be folded over nor can they be torn from the main body of the hide itself.

By means of the above described apparatus and the method the treatment of the leather is conducted in operational paths having the form of sections of circles,

the beginning of the section being made only when the working tool is directly above major portion of the hide and proceeds in a direction away from the major portion to the periphery of the hide. The direction of the movement of the front treating elements is initially directed toward the direction of movement of the conveyer and then to the external peripheral portions of the conveyer, i.e., the hide. In this manner the danger of damaging either the front or rear leg portions or any of the peripheral edges of conveyer are obviated. Similarly the rear working elements are caused to operate in a similar sector of the circle. The initial or beginning portion of the sector taking place only when the working element is directly above the major portion of the hide and the direction of working being such that the elements move to the rear initially and they outwardly toward the peripheral edges of the hind quarter of the hide. In this manner the hind leg portions of the hide are worked approximately lengthwise of the axis of their shape which results in keeping these parts from being torn or folded over during the working operating. The direction and treatment of each of the elements in each of the tandem pairs is in the opposite direction. This is the case as well with each of the aligned front and rear elements of each of the tandem pairs, thus in the embodiment as shown wherein four elements are provided, each of the elements appears to stand at the corner of a rectangle and rotate about a vertical axis drawn through such corner. Thus the paths of movement are from within the rectangle toward the exterior of the rectangle.

FIG. 3 depicts schematically a type of apparatus for each of the treatment devices which may be used in carrying out the present invention. Only one such treatment device 3 is shown in detail since they are essentially all the same. Fixed to the upper edge of the hub 31 and extending vertically of the device 3 is a shaft 100 which is journaled for rotation about its central axis in a tubular housing, which is adjustably secured to the frame F of the machine. A sprocket wheel 101 is mounted on its upper end and is connected by a chain 102 to a suitable drive means such as a motor or the like. The chain may be connected to the aligned treatment device 5, if desired for common operation and its speed may be regulated by control of the motor, or the use of interpositioned sprocket or gear train. The shaft 100 is vertically positioned along the marginal edge of the conveyor 2 as earlier mentioned. Mounted to extend laterally of the hub 31 are a plurality of webs 103 at the outer end of which are vertically mounted hydraulic cylinders 104 from which a piston rod 105 extends; mounted at the end of the piston rod is a holder 106 to which the treatment element 32 is removable secured by manually operable screw means 107. The holder 106 and element 32 are planar members arranged to be perpendicular to the conveyor, as earlier described along the line 10 and to be fixed in that position at the end of the piston 7 so that the edge of the element 32 lies parallel to the plane of the conveyor, as seen in FIG. 3.

The hub 31 is hollow and forms a reservoir 108 for hydraulic fluid. Surrounding the reservoir are four cylinders 109. Each cylinder has an inlet 110 communicating with the reservoir 108 and an outlet 111 communicating with the upper end of one of the cylinders 104. A piston 112 reciprocates within the cylinder 109 and has a rod 113 extending upwardly alongside the shaft

100. A link 114 is fixed to the upper end of each rod and extending radially inwardly to the shaft 100. At the end of each link is a roller 115. Each cylinder 109 has a return spring 119 which normally urges the piston 112 upwardly. A tension spring 118 is mounted between the web and each of the holders 107 to urge the holder 107 normally upward.

The housing of the shaft 100 is itself surround by a housing 120 which latter housing is movable with respect to the shaft in a vertical direction. A hydraulic pneumatic or similar motor 121 is provided to raise and lower the housing. Mounted at the lower end of the housing is a quarter circular cam 122 which is adapted to engage the roller 115 of the link 114.

The motor 121 may be controlled by a suitable relay system, memory system or sensing system, dependent upon the passage of a hide 1 over the conveyor, and after a suitable interval to cause the housing 120 to be lowered and thereafter raised.

In operation the shaft 100 is rotated via actuation of chain 102, carrying the elements 32 to be swung about the central axis of shaft 100 at the ends of the webs. On sensing the passage of a hide or at a predefined interval, the motor 121 causes the housing 120 to descend so that the quarter cam 122 engages the rollers 115. As the cam engages a roller that roller 115 causes the piston 112 to be depressed covering inlet 110 and forcing fluid into conduit 111 thus causing the corresponding element 32 to be lowered against the hide on the conveyor. As the cam 122 leaves the roller 115 the springs 109 cause the piston 112 to rise allowing the fluid to return to the reservoir and the element 32 to rise.

By arranging the cam 122 and the elements 32, etc., in a predetermined angular relationship, the operation of the present invention can be easily effected whereby the elements 3, 4, 5 and 6 can be lowered along the transverse lines 10 and 12 respectively, so that no interference with the leading or trailing edges of the workpiece occur, and the operation is obtained as previously described.

The treating elements may be in the form of spreaders, scrapers or knives as conventional and one may be easily replaced with the other. As is also conventional, spray means for the moisture treatment or coating of the hide may be employed simultaneously with the mechanical treatment.

As a result of the method and apparatus of the present invention the hide is treated with less force and consequently is distorted and destroyed to a lesser degree. As a result the hide has improved quality. This holds true even for hides having very irregular shapes. Furthermore, because of the overlapping arrangements of the working element in sections B—B and C—C, the hide is worked to a more uniformed degree and a uniform thickness leather is obtained. Additionally the working elements engage the entire surface of the leather so that a regular surface throughout the entire area of the leather is performed. This is most significant with respect to the peripheral portions of the leather and especially the leg parts which prior devices were never capable of being automatically treated in a regular fashion.

Various changes and modifications may be made to the method as well as to the apparatus. Some of these changes have been suggested in the present disclosure, others will be obvious to those skilled in the art. The present disclosure therefore is to be taken as illustrative

only and not limiting of the scope of application of the present invention.

What is claimed:

1. A method for the surface treatment of discontinuous sheet material such as an animal hide comprising the steps of carrying said material on a continuously moving linear conveyer, providing a pair of working devices in tandem along one side of said conveyer, locating each device in said tandem pair in a horizontal plane spaced from the conveyer to rotate about an axis perpendicular to the conveyor and aligned with the edge thereof, rotating the working device upstream of said conveyor counter to the direction of movement of said conveyor, rotating the working device downstream of said conveyor in the direction of movement of said conveyor, and causing said devices to engage the material initially at a line normal to the direction of movement of said conveyer and thereafter maintaining such engagement in a sector of the circle along an arcuate path toward the edge of said one side of said conveyor.

2. The method according to claim 1 wherein each of said working devices comprise a plurality of working elements uniformly arranged about the central axis and extending radially therefrom so as to successively engage the material.

3. The method according to claim 2 providing two pair of tandem working devices, arranging the devices of the second pair to rotate about axes aligned with the edge of said conveyor opposite to the first of the tandem pair, causing each of said devices in said second

pair to engage a portion of the material at a line normal to the direction of movement of said conveyer and thereafter in a sector of circle along an arcuate path toward the outer edge of said conveyer.

5. The method according to claim 3 wherein each of the working devices is caused to rotate in a direction opposite to that of its next adjacent device.

5. The method according to claim 3 wherein the corresponding devices in each of the first and second pairs are aligned along an axis transverse to the direction of movement of said conveyer and are caused to rotate in opposite directions.

6. Apparatus for the surface treatment of a discontinuous sheet of material such as an animal hide or the like comprising a linear moving conveyer, at least one pair of working devices arranged in tandem along one side of said conveyer, means for rotatably mounting said device in a horizontal plane spaced from said conveyer, means for rotating the upstream one of said devices counter to the direction of movement of said conveyor and the downstream one of said devices in the direction of movement of said conveyor, and means for causing said devices to engage the material on said conveyer initially along a line normal to the direction of movement of said conveyer and to remain in engagement thereafter in a sector of a circle along respective arcuate paths toward the edge of said conveyer.

7. The apparatus according to claim 6 including two pair of devices each pair being arranged respectively along one side of the conveyor.
